UNITED STATES PATENT OFFICE.

PAUL J. SIMMEN, OF LOS ANGELES, CALIFORNIA.

CAB SIGNAL SYSTEM.

1,140,623.

Specification of Letters Patent. Patented May 25, 1915.

Application filed January 22, 1909. Serial No. 473,711.

To all whom it may concern:

Be it known that I, PAUL J. SIMMEN, a citizen of the United States, residing at Los Angeles, in the county of Los Angeles and State of California, have invented certain new and useful Improvements in Cab Signal Systems, of which the following is a full, clear, and exact description.

My invention relates to signal systems for trains and locomotives and more particularly to a system by which a signal is maintained in a cab under safety conditions, effected by the presence of electrical energy in intermittently spaced contact plates, tappets or inductive circuits along the trackway over which the train passes. All or practically all danger conditions arise from track conditions of various sorts and it is a simple matter to effect the electrification or the non-electrification of a contact plate, rail, tappet or inductive circuit in the path of the train, by the occurrence of safety and danger conditions, respectively. Or it is possible to cause electromagnetic waves to be emitted at a particular point of the trackway and which influence electric currents in a circuit of the train. In the most convenient cases, however, the danger track conditions produce a local electrification, excitation or wave emanation at a certain point or points of the trackway, so that the effect on the train is occasional rather than constant. This gives rise to two serious difficulties which so far as I am aware have been inherent in the systems hitherto proposed.

It is the object of my present invention to overcome these difficulties.

The first difficulty arises from the fact that a mere temporary or momentary signal is not a sufficient warning of danger conditions ahead where the danger conditions are continuing. It is in every way important if a danger signal is used and relied upon at all, that it should be of such a character as to create and continue an alarm as long as the danger conditions continue. The second difficulty encountered in systems of the above character is that electrification or wave emanation or other presence of energy is an unsafe and discredited plan of actuating a danger alarm upon which any reliance is placed, because there are numberless ways in which the energy might be diverted or dissipated from the relation where it should actuate the alarm, even assuming that the danger conditions exist. Reliance can only

be had upon the absence rather than the presence of energy to denote alarm conditions. This last matter is so serious that it is practically imperative to have the danger conditions indicated by the absence of energy rather than the presence of it. But the last condition is not of a nature naturally adapted to overcome the first difficulty mentioned, since the continuous and uninterrupted actuation of an alarm during danger conditions and vice versa is not readily secured by the intermittent absence of energy at predetermined points along the trackway. I overcome these difficulties by the construction and combination as hereinafter set forth and claimed.

In the drawings: Figure 1 is a diagrammatic view showing some of the prominent features of a cab signal system embodying the principles of my invention. Fig. 2 illustrates certain modifications which may be made. Fig. 3 diagrammatically shows a series of ramp rails and their relation to parts operated thereby carried by the train or vehicle.

Referring to the drawings in which like parts are designated by the same reference sign, 1 designates a contact, plate, tappet or rail section alongside the usual track rail 2 and which is provided at points along the roadway where danger or signal indications are to be made.

3 denotes a shoe movably attached to the train and having a contact block 4 in the path of the rail section 1. I have illustrated the shoe 3 pivoted at 4' to a fixed part 5 of a truck of the train and normally depressed by its own weight and by a spiral spring 6.

7 denotes a rod guided to move vertically in the frame part 5 and resting on or connected to the shoe 3 within said spiral spring 6. This rod is guided to move vertically by any suitable bearing collars 8, 8'.

9 denotes a bearer on the rod 7 which is advantageously made in the form of a rounded disk clamped between a pair of adjustment collars 10.

12 indicates a magnet of which I prefer the solenoid type having a plunger 13 depressed by gravity and by a spiral spring 14 within the winding 12 and abutting against a cap 15 thereon. Under the double impulse of the spring and gravity it is certain, within all ordinary possibility, that the plunger will fall if the magnet is not ener-

gized, assuming the absence of other restraining means. With my invention the falling of this plunger 13 is a danger indication under any circumstances, and puts an obligation on the engineer to stop or slow down. The falling of this plunger may be due to mechanical defects in the apparatus or defects in the electrical circuits as well as a proper danger or signal actuation, but in any case the train should stop and the engineer investigate until the cause is known. If this rule is observed, absolute safety is insured.

The fact has been referred to that the position of energy due to danger conditions occurs only at predetermined points along the trackway in accordance with my present invention. Under these circumstances the magnet 12 is deenergized at intermediate lengths of the trackway in any case, whether there are danger conditions or not. The falling of the plunger 13 would be an improper indication under these circumstances and I provide mechanical means for maintaining the safety signal position of the plunger 13 throughout the intermediate portions of the trackway between these points or stations where the energy emanations above referred to occur, so that if a block is open the engineer will have a continuing warrant to proceed therein until the next signal or energy emanation point is reached. Different mechanisms embodying the principles of my invention may, of course, be employed, but I prefer to use a depressible rubber tipped finger 18, which is kept pressed against the core or plunger 13 between signal points. During the passage of the signal points or stations, this finger is mechanically and preferably positively displaced out of contact with the plunger, so that the latter is free to fall or move according to the danger or safety conditions. In the drawings the finger 18 is made in the form of a sleeve having a rubber tip 19 and a flange 20 engaged by spring 21 and guided in a recess of a block or frame 22 which also guides the lower end of the plunger 13 in its movement. The movement is further guided and steadied by a projecting extension 23 which is received in a bearing 24 of the frame 5.

25 denotes a stud with a round head 26 in the path of depression of the bearer 9. This stud is guided by the sleeve 18 and the extension 23 and is impelled outwardly therefrom by a spring 28.

29 denotes a wedge on the rod 7 which engages a portion 23' of the extension 23 and causes the finger 18 to be positively withdrawn from its engagement on the plunger 13, whenever the train is passing signal points.

Before considering the operation I will refer to a practical means for giving an

audible alarm when the core or plunger 13 drops.

Many types of audible or visual alarm may be adopted, or the plunger 13 can be exposed so as to be visible and conspicuous and itself constitute a signal.

30 denotes a port in the block 22 which is adapted to register with a corresponding port or channel 31 in the plunger 13 when the latter is in its lowermost or dropped position. On the outside of the plunger there is a cavity 32 communicating with a source of air or other pressure pipe 33 so that when the plunger 13 is dropped, as shown, air or steam will pass through the cavity 32, 80 through the plunger, through the port 30 and pipe 34 to a whistle or similar signal 35. When the plunger 13 is elevated, its channel 31 is drawn out of alinement with the port 30 so that the flow is cut off and the signal silenced. This is merely an example of an audible alarm which may be used.

I have referred to the fact that the magnet 12 is periodically energized by an electrical current. This current may be derived either conductively or inductively from the track circuit. I have illustrated both arrangements, that of Fig. 1 being of the conductive type and that of Fig. 2 being of the inductive type. In Fig. 1 a circuit 1' is established from the rail 1 to the insulated block 4 and through the magnet 12 to the wheel axles or ground. In the type of Fig. 2 an induction coil winding m^2 is connected in a circuit m^2 , with the magnet 12, and is so fixed on the train or locomotive as to travel in inductive proximity to a stationary inductive winding m^3 in the trackway. A periodical current in winding m^3 induces an alternating current in the circuit m^2 , which acts on the magnet 12 to energize the same and attract the plunger nearly as efficiently as a direct current if the plunger is properly laminated. The rail section 1, or the winding m^3 receive their current from any suitable or desired source in any well known and obvious manner, the only essential requisite being that energy is present during safety conditions and absent in danger conditions.

In use the train proceeds along the trackway and intermittently passes the rail sections 1 or the windings m^3 as the case may be. In the latter instance some means such as the ramp rail section 1 is provided to elevate the shoe 3 or its equivalent during the passage of the coil m^2 past such winding m^3 . The mechanical raising of the shoe 3 produces an upward displacement of the rod 7 of the bearer 9, so that the rubber tipped finger 18 is impelled outward and releases the plunger 13. The plunger then drops by gravity and the spring 14, unless it is sustained against this influence by the magnet 12, which receives its energy

from the energy emanations of the trackway, as already described. If in case of danger conditions or any other improper or defective working, this energization of the magnet does not occur, its plunger drops and a whistle or other alarm signal is given. But if the block ahead is safe and the apparatus is normal, and without defect, it is proper to give the engineer a warrant to proceed at full speed through the length of such ensuing block and this warrant is supplied by the action of the rubber tipped finger 18, which resumes its grip on the plunger at the very instant when the energization of the magnet 12 is discontinued. The engineer therefore retains a present and constantly observable indication of safety throughout the safe block, as is desirable, but this mechanically enforced safety indication terminates at the end of such block and an entirely new warrant to proceed through the next block must be obtained. The latter cannot be had unless such ensuing block is safe and unless all the apparatus and circuits are normal and undefective; so that a virtual test out of the apparatus and an entirely new warrant of clear signal conditions ahead is obtained at each block entrance before the engineer can traverse it. All these functions are, however, automatic and require no strain or attention on the engineer, who merely needs remember that while the plunger 13 is elevated, he is safe to proceed, but when the plunger falls, he must infallibly and invariably stop, because such fall can only occur through actual danger or defective apparatus.

In the foregoing description I have employed the term mechanically operated, which I desire to be understood in the sense of an operation produced by any physical force of any description not electrical. It is evident that many equivalents of such a mechanical or physical operation can be employed within the spirit and scope of the present invention.

What I claim is:

1. In a railway signal system, a trackway, means for producing electrical energy emanations at spaced separated points along said trackway, a movable part carried by the train having a bias toward danger indicating position, means on the train actuated by such energy emanations for holding said part in safety indicating position during the continuance of such emanations, and mechanically operated means for normally holding said part in said safety indicating position throughout the intervals between said emanations.

2. In a railway signal system, a trackway, means for producing electrical energy emanations at spaced separated points along said trackway, a movable part carried by the train having a bias toward danger indicat-

ing position, means on the train actuated by such energy emanations for holding said part in safety indicating position during the continuance of such emanations, mechanically operated means for normally holding said part in safety indicating position throughout the intervals between said emanations, and means for releasing said movable part from the action of said mechanically operated means during said emanations.

3. In a railway signal system, a trackway, means for producing electrical energy emanations at spaced separated points along said trackway, a movable part carried by the train having a bias toward danger indicating position, means on the train actuated by such energy emanations for holding said part in safety indicating position during the continuance of such emanations, mechanically operated means for normally holding said part in safety indicating position throughout the intervals between said emanations, and positively acting means for releasing said movable part from the action of said mechanically operated means during said emanations.

4. In a railway signal system, a trackway, means for producing electrical energy emanations at spaced separated points along said trackway, a movable part carried by the train having a bias toward danger indicating position, means on the train actuated by such energy emanations for holding said part in safety indicating position during the continuance of such emanations, mechanically operated means for normally holding said part in safety indicating position throughout the intervals between said emanations, and means displaced by the passage of a train past said points for releasing said movable part from the action of said mechanically operated means.

5. In a railway signal system, a trackway, means for producing electrical energy emanations at spaced separated points along said trackway, a magnet on the train energized by such energy emanations, an armature attracted by said magnet, and mechanically operated means for maintaining said armature in such attracted relation during the intervals between said emanations.

6. In a railway signal system, a trackway, means for producing electrical energy emanations at spaced separated points along said trackway, a magnet on the train energized by such energy emanations, an armature attracted by said magnet, mechanically operated means for maintaining said armature in such attracted relation during the intervals between said emanations, and positively acting means for releasing said armature during said emanations.

7. In a railway signal system, a trackway, means for producing electrical energy ema-

- 5 nations at spaced separated points along said trackway, a magnet on the train energized by such energy emanations, an armature attracted by said magnet, mechanically operated means for maintaining said armature in such attracted relation during the intervals between said emanations, and means for releasing said armature during said emanations.
- 10 8. In a railway signal system, a trackway, means for producing electrical energy emanations at spaced separated points along said trackway, a magnet on the train energized by such energy emanations, an armature attracted by said magnet, mechanically operated means for maintaining said armature in such attracted relation during the intervals between said emanations, and means for releasing said armature during said emanations.
- 15 9. In a railway signal system, a trackway, means for producing electrical energy emanations at spaced separated points along said trackway, a movable part carried by the train having a bias toward danger indicating position, means on the train actuated by such energy emanations for holding said part in safety indicating position during the continuance of such emanations, and mechanically-operated means for normally holding said part in said safety indicating position throughout the intervals between said emanations, the last mentioned means being rendered inoperative during the continuance of said energy emanations.
- 20 10. In a railway safety system, means for producing electrical energy emanations at spaced separate points along the trackway, a fluid-actuated device carried by the train, a movable device on the train provided with means for controlling the supply to said fluid-actuated device, said movable device being biased to one position, means on the train actuated by such energy emanations for holding said part out of its biased position during the continuance of such emanations, and mechanically-operated means for also holding said part out of said biased position throughout the intervals between said emanations, the last-mentioned means being rendered inoperative during the continuance of said energy emanations.
- 25 11. In a cab railway signal system, a signaling device on the cab, a movable controlling part therefor, said signaling device indicating danger when said part occupies one position and safety when it occupies another position, means automatically controlled by the moving train for emplacing said part in safety indicating position, and a separate and distinct mechanical appliance for independently holding said part in said safety position after the emplacing means has ceased to act upon said part.
- 30 12. In a railway signaling system, a trackway, means for producing electrical energy emanations at spaced points along
- 35 said trackway, a movable part carried by the train having a bias toward danger indicating position, means on the train for holding said part in safety indicating position throughout the intervals between said emanations, a mechanical appliance for rendering said last-mentioned means inoperative, means disposed at intervals along said trackway for actuating said appliance, and electro-magnetic means co-operating with said holding means for also holding said parts in safety indicating position when said first-mentioned holding means is inoperative.
- 40 13. In a railway safety system, means for producing electrical energy emanations at spaced separate points along the trackway, a fluid-actuated device carried by the train, a movable device on the train provided with means for controlling the supply to said fluid-actuated device, said movable device being biased to one position, means on the train actuated by such energy emanations for holding said part out of its biased position during the continuance of such emanations, and mechanically-operated means for also holding said part out of said biased position throughout the intervals between said emanations, the last-mentioned means being rendered inoperative during the continuance of said energy emanations.
- 45 14. In a railway signaling system, the combination with a movable vehicle, of a signal carried thereby, means also carried by the vehicle for actuating the signal, trackside mechanism for intermittently controlling the actuating means, and means mounted on the vehicle for maintaining the signal in the condition in which it is placed by the actuating means during the periods when the operating means is inactive.
- 50 15. In a railway signaling system, the combination with a movable vehicle, of a signal carried thereby, means also carried by the vehicle for actuating the signal, trackside mechanism for intermittently controlling the actuating means, and means mounted on the vehicle for maintaining the signal in the condition in which it is placed by the actuating means during the periods when the operating means is inactive, and said maintaining means being inactive during the periods when the trackside operating mechanism is in co-operative relation with the signal actuating means.
- 55 16. In a railway signaling system, the combination with a movable vehicle, of a signal carried thereby, means also carried by the vehicle for actuating the signal, trackside mechanism for intermittently controlling the actuating means, and means mounted on the vehicle for maintaining the signal in the condition in which it is placed by the actuating means during the periods when the operating means is inactive, and said

5 maintaining means being moved to inactive relation by the trackside operating means during the periods when the trackside operating mechanism is in coöperative relation with the signal actuating means.

17. In a railway signaling system, the combination with a movable vehicle, of a signal thereon, electrical means carried by the vehicle for maintaining the signal in a predetermined position, electrical trackside mechanism intermittently moved into and out of coöperative relation with the electrical means during the passage of the vehicle to intermittently operate the electrical means, and mechanical means mounted on the vehicle and acting to hold the signal in said predetermined relation during the periods when the electrical means is out of coöperative relation with the trackside electrical operating mechanism.

18. In a railway signaling system, the combination with a movable vehicle, of a signal thereon, electrical means carried by the vehicle for maintaining the signal in a predetermined position, electrical trackside mechanism intermittently moved into and out of coöperative relation with the electrical means during the passage of the vehicle to intermittently operate the electrical means, and mechanical means mounted on the vehicle and acting to hold the signal in said predetermined relation during the periods when the electrical means is out of coöperative relation with the trackside electrical operating mechanism, said holding means being inactive during the periods when the trackside electrical operating mechanism is in coöperative relation with the electrical means.

19. In a railway signaling system, the combination with a movable vehicle, of a signal thereon, electrical means carried by the vehicle for maintaining the signal in a predetermined position, electrical trackside mechanism intermittently moved into and out of coöperative relation with the electrical means during the passage of the vehicle to intermittently operate the electrical means, and mechanical means mounted on the vehicle and acting to hold the signal in said predetermined relation during the periods when the electrical means is out of coöperative relation with the trackside electrical operating mechanism, said holding

means being moved to inactive relation by 55 the trackside operating mechanism during the periods when said trackside mechanism is in coöperative relation with the electrical means.

20. In a railway signaling system, the combination with a movable vehicle and traffic controlling means thereon, of means for normally maintaining the traffic controlling means in safety position, means for periodically operating the maintaining 65 means to release the traffic controlling means, electrical means for maintaining the traffic controlling means in safety position, and means for inducing currents in the electrical means when the first maintaining means 70 is released, to cause said electrical means to maintain the traffic controlling means in safety position.

21. In a railway signaling system, the combination with a movable vehicle and 75 traffic controlling means thereon, of means for normally maintaining the traffic controlling means in safety position, electrical means for maintaining the traffic controlling means in safety position, and mechanism for simultaneously and periodically operating the first maintaining means to release the traffic controlling means and inducing currents in the electrical means, to cause the latter to maintain the traffic controlling means in 85 safety position when released by said first maintaining means.

22. In a railway signal system, the combination with a movable vehicle, of a signal thereon, means for maintaining said signal 90 in a predetermined condition, means for intermittently releasing said signal to permit it to assume a different condition, and electrical mechanism for normally maintaining the signal in its first mentioned condition 95 when released, said mechanism including means mounted on the vehicle for receiving induced currents, signal-maintaining means actuated by such induced currents, and means along the wayside for intermittently 100 causing induced currents in the said receiving means.

In witness whereof, I subscribe my signature, in the presence of two witnesses.

PAUL J. SIMMEN.
